UNITED STATES PATENT OFFICE.

ALDEN L. McMURTRY, OF SOUND BEACH, CONNECTICUT.

APPARATUS FOR SCENIC AND MUSICAL EFFECTS.

1,071,939.

Specification of Letters Patent.

Patented Sept. 2, 1913.

Application filed May 6, 1911. Serial No. 625,445.

To all whom it may concern:

Be it known that I, ALDEN L. McMURTRY, a citizen of the United States, and a resident of Sound Beach, in Fairfield county and 5 State of Connecticut, United States of America, have invented certain new and useful Improvements in Apparatus for Scenic and Musical Effects, of which the following is a specification.

10 My invention relates to apparatus for producing novel scenic and musical effects, and is especially designed for theatrical purposes.

I will describe my invention in the following specification and point out the novel features thereof in the appended claims.

Referring to the drawings, Figure 1 shows a portion of a representation of a staff of music with various notes thereon, 20 together with diagrammatic views of certain electrical apparatus and connecting circuits. Fig. 2 is a diagram of a modification of some parts of the apparatus and shows a development of my invention. In 25 Fig. 3 a portion of a modified form of circuit controller is shown in sectional side elevation. Figs. 4 and 5 show one of the notes with its electrical attachment in front elevation, and sectional plan view, respectively. 30 Like characters of reference designate corresponding parts in all of the figures.

10 designates a pictorial representation of a staff of music with notes thereon. This may be a drop-scene but is preferably constructed on a frame which may be either supported on the stage or suspended in desired position. The staff may be painted, and so may the notes, or the latter may be cut out of some insulating material and 35 fixed to the material on which the staff is pictured. The notes are designated in the drawings by 11. Through each note project a pair of fixed electrodes 12 and 13. One of these electrodes for each note is 40 connected with a common wire 14. From the other electrode of each note runs a separate and independent conductor to a circuit controller 20, as will be specifically pointed out hereinafter.

50 15 is a battery which is connected through a switch 16 with the primary winding of

an induction coil 17. The wire 14 is connected with one of the terminals of the secondary winding of this coil, and the other terminal of this winding is connected with 55 the controller 20 by a wire 18. If desired a condenser 19 may be connected between the wires 14 and 18.

The circuit controller 20 comprises a flat rotary disk 21 of insulating material, and 60 some arrangement for rotating it about its axis at a slow rate of movement. For example, the periphery of the disk may be toothed or provided with a gear in which meshes a manually rotatable pinion 22. On 65 the disk are fastened in desired positions a plurality of contacts such as 23, 24, 25, 26, 27, 28 and 29.

30 is a stationary contact maker which is suitably held above the disk 21 in such a 70 position as to bear upon the disk contacts when they are moved under it. The wire 18 is connected with this contact maker 30.

Before more particularly pointing out the modifications which are shown I will de 75 scribe the operation of the apparatus which is illustrated in Fig. 1.

When the switch 16 is closed, the induction coil 17, which is of the vibratory type, will be energized. Electrical impulses in 80 rapid succession will then be set up in the secondary winding of this coil. The device 10 with its staff and notes is placed in desired position and the stage partly darkened. Now, when the pinion 22 is rotated 85 the disk will revolve and the contact 23 will be brought into engagement with the contact 30. The contact 23 is connected by a wire 23A with the fixed electrode 13 of the first note 11. As its other electrode 12 is 90 always connected with the wire 14, the terminals of the secondary winding of the induction coil will be connected with the two electrodes 12 and 13, and this will cause sparks to jump across the gap in front of this 95 first note as long as the contact 23 remains under the contact 30. Further movement of the disk 21 brings contact 24 under contact 30, and as this is connected by a wire 24A with the second note 11, the sparks will now 100 appear in front of it. In the same way the other contacts 25, 26, 27, 28 and 29, when

they come under the contact 30, will cause the other notes shown on the staff to be successively illuminated by the sparks. It is to be noted that the arc-lengths of the disk contacts correspond with the time values of the notes on the staff. They are also shown at different distances from the axis of rotation for use with the modification shown in Fig. 2, but so far as the arrangement in Fig. 1 is concerned, the disk contacts might all be an equal distance from the axis of the disk.

It is to be understood that this apparatus is to be used in conjunction with music, instrumental or vocal, and that as the music progresses, the notes on the staff, which correspond with the music, become successively illuminated as the particular tone which it represents is played or sung.

Electric sparks jumping across gaps like those formed between the electrodes 12 and 13 make a considerable noise. By suitably adjusting the coils which induce these sparks, their frequency may be varied to cause this noise to have a desired pitch. In the diagram shown in Fig. 2, an arrangement for utilizing this fact is illustrated. A plurality of induction coils are used, in this case eight, corresponding with the notes of one octave of the major scale. These coils are designated in the drawings by 17F, 17G, 17A, 17B_b, 17C, 17D, 17E, 17f, and each coil is so adjusted that it may cause sparks to jump across air gaps between fixed electrodes in the scale 10, at such frequency as to produce a sound of a pitch, like that represented by its corresponding note or notes 11, on the scenic scale. In this case the contact maker 30A comprises a plurality of independent contacts, one being provided for each of the induction coils. When this arrangement is used the rotation of the disk 21 first brings the disk contact 23 under that one of the contacts of the contact maker 30A which is designated in Fig. 2 by the letter C. This is connected with the coil 17C. When these contacts come together it causes the sparks which jump across the face of the first note 11 to make a sound, the pitch of which is that of the note C shown on the staff. The disk contact 24 next comes under contact B_b which is connected with the coil 17B_b, and this combination causes sparks to jump across the face of the second note on the staff in proper frequency to produce a sound on the pitch of B_b. Similarly, the other notes will be successively illuminated and the sparks which illuminate them will produce the tune which the notes on the staff represent, and this effect may be used either by itself or in conjunction with the simultaneous production of the same tune by voice or musical instrument, or both.

In Fig. 3 a portion of a circuit controller

is shown which is arranged to open and close both the primary and the secondary circuits of the induction coil. In this case a rotary disk 21 is provided as before. On one side of this disk are contacts such as 23 to which the conductor 23A is connected. The contact maker C is shown in this figure somewhat in detail and resting upon the contact 23. These contacts, as has been shown, are in the secondary circuit of the induction coil 17C. On the opposite side of the disk 21 are affixed other contacts such as 23', with which a stationary contact c coacts to open and close a circuit between contacts 31 and 32. These are placed in the diagram of Fig. 2 in the position indicated therein by the numeral 33, and control the circuit of the primary winding of the coil 17C. These secondary and primary circuit controllers are of course arranged to work together, and a similar pair of them is provided for each note on the scale 10. The operation is like that previously described, but the coils in this case are only energized during such intervals as those in which the voltage induced by them is utilized.

What I claim is.—

1. The combination with a scenic representation of a musical note, of means for causing electric sparks to jump across the face of said note.

2. The combination with a scenic representation of a plurality of musical notes, of means for causing electric sparks to jump across the face of said notes successively.

3. The combination with a scenic representation of a musical note, of means for causing electric sparks to jump across the face of said note at such frequencies as to produce a sound at the pitch of said note.

4. The combination with a scenic representation of a plurality of musical notes, of means for causing electric sparks to jump across the faces of the notes at such frequencies as to produce sounds at the respective pitches of said notes.

5. The combination with a scenic representation of a musical note, of a pair of electrodes for said note, a battery, an induction coil, electrical connections, and a circuit controller in said connections.

6. The combination with a scenic representation of a plurality of musical notes, of a pair of electrodes for each of the notes, a battery, a plurality of induction coils, each adjusted to produce electrical impulses at different frequencies, electrical connections, and a circuit controller in said connections.

7. The combination with a scenic representation, of a plurality of successive musical notes, of a pair of electrodes for each of said notes, a battery, a plurality of induction coils, each adjusted to produce electrical impulses at different frequencies, elec-

trical connections, a circuit controller between the coils and the notes in said connections, said circuit controller being arranged to connect successively and during desired intervals of time each note with its respective coil, and means for actuating the circuit controller.

In testimony whereof I have signed my name to this specification in the presence of two subscribing witnesses.

ALDEN L. McMURTRY.
